US0D1023405S

(12) **United States Design Patent** (10) **Patent No.:** **US D1,023,405 S**
(45) **Date of Patent:** **** Apr. 16, 2024**

(54) **PICTURE LIGHT**

(71) Applicant: **Shenzhen Yimai E-commerce Co., Ltd.**, Shenzhen (CN)

(72) Inventor: **Fandong Zeng**, Shenzhen (CN)

(73) Assignee: **Shenzhen Yimai E-commerce Co., Ltd.**, Shenzhen (CN)

(**) Term: **15 Years**

(21) Appl. No.: **29/920,381**

(22) Filed: **Dec. 11, 2023**

(51) LOC (14) Cl. **26-05**

(52) U.S. Cl.

USPC **D26/87**

(58) **Field of Classification Search**
